UNITED STATES PATENT OFFICE.

THOMAS C. WHITEHEAD, OF DETROIT, MICHIGAN.

HOLD OVER.

Application filed June 14, 1926. Serial No. 116,029.

This invention relates to mechanical refrigerating apparatus and more particularly to a boiler or expansion coil unit for use in such an apparatus.

5 In the boiler or expansion coil units now in use the body or core for supporting the refrigerant receiving tube has usually been formed of metal having a high coefficient of heat transmission and being so proportioned 10 as to adapt the body to act as a holdover, or, in other words, to respond slowly to changes in temperature. Such a construction is very expensive to manufacture and it is therefore the object of the present invention to provide a construction which is just as efficient a holdover as the devices heretofore used and which is very much 15 cheaper to manufacture.

With these and other objects in view, the 20 invention resides in certain novel features of construction, combinations and arrangements of parts as will be more fully described and particularly pointed out in the appended claims.

25 In the accompanying drawings:

Figure 1 is a perspective view of a boiler or expansion coil unit constructed in accordance with my invention;

30 Figure 2 is a vertical longitudinal sectional view through the device;

Figure 3 is a modification showing a slightly different arrangement of the tubes.

Referring now particularly to the drawings wherein like reference characters indicate like parts, it will be noted that there is illustrated a body 10 formed preferably of sheet metal or any similar inexpensive material. This body in the form herein shown is shaped preferably rectangularly in 35 cross section to provide the top 11, bottom 12 and sides 13. The body is formed preferably with openings or passages 14 therethrough which may be formed by means of partition walls 15. The openings or passages 14 not only provide for a free and efficient circulation of the air through the 40 unit, but also provide compartments for freezing water cubes, fruits and the like.

The refrigerant receiving tube constituting the expansion coil is indicated by the 45 reference character 16 and is shown as wound around the body or core 10 with the coils or convolutions thereof arranged side by side longitudinally of the body. In the 50 present invention this tube is formed with

a larger diameter than the tubes usually employed in this connection and as a result thereof a larger volume of refrigerant will circulate around the body 10 without the necessity of providing additional tubing.

55 In view of the fact that the body 10 is formed preferably of an inexpensive sheet metal construction, which of course does not have a high coefficient of heat transmission, some other means must necessarily be provided to act as a holdover. In the present instance I provide what will hereafter be termed a water tube, which is designated at 17, and is also wound around the body core 10 upon the refrigerant receiving tube 16 in such a manner that the convolutions of the water tube 17 nest between the convolutions of the tube 16, as clearly shown in Figure 2. Such an arrangement provides 60 sufficient thermal contact between the tubes to form an efficient holdover of the water tube 17. Preferably a non-freezing solution of calcium chloride and water is circulated through the tube 17. It has been found 65 that such a solution has a high thermal capacity and that a very efficient holdover is provided which is in every way equal, if not superior, to the type heretofore used.

70 A slightly different arrangement of tubes is shown in Figure 3 in which two separate water tubes 18 and 19 are provided, one interposed between the body 10 and the coils of the refrigerant receiving tube, and the other resting on top of the aforesaid coils so that the convolutions of the water tubes 75 are nested between the convolutions of the refrigerant receiving tube at diametrically opposite sides thereof.

80 The body is preferably formed with outwardly laterally extending flanges 20 at the ends thereof forming shoulders or stops 21 to prevent any relative longitudinal movement between the different coils and the body, these flanges being also preferably of sufficient dimensions as to project beyond 85 and conceal the convolutions of the tubes 16 and 17 when the unit is viewed from the end thereof.

90 From the foregoing it will be apparent 95 that an expansion coil unit has been provided which is simple in construction, efficient in operation and cheaply manufactured.

100 While it is believed that from the foregoing description, the nature and advantage 105

of my invention will be readily apparent, I desire to have it understood that I do not limit myself to what is herein shown and described and that such changes may be resorted to when desired as fall within the scope of what is claimed.

What I claim as my invention is:

1. In a mechanical refrigerating apparatus, an expansion coil unit comprising a refrigerant receiving tube, tubing for a non-freezing solution in thermal contact with said refrigerant receiving tube and serving as a holdover, and a body constituting a core around which said tubes are wound.
2. In a mechanical refrigerating apparatus, an expansion coil unit comprising a refrigerant receiving tube, tubing for a non-freezing solution and a body constituting a core around which said tubes are wound, the convolutions of the tubing containing the non-freezing solution being nested between the convolutions of the refrigerant receiving tube and serving as a holdover.
3. In a mechanical refrigerating apparatus, an expansion coil unit comprising a refrigerant receiving tube, tubing for a non-freezing solution in thermal contact with said refrigerant receiving tube at diametrically opposite sides thereof and serving as a holdover, and a body constituting a core around which said tubes are wound.
4. In a mechanical refrigerating apparatus, an expansion coil unit comprising a refrigerant receiving tube, tubing for a non-freezing solution, a body constituting a core around which said tubes are wound, the con-

volutions of the tubing containing the non-freezing solution being nested between the convolutions of the refrigerant receiving tube at diametrically opposite sides thereof and serving as a holdover.

5. In a mechanical refrigerating apparatus, an expansion coil unit comprising a refrigerant receiving tube, tubing for a non-freezing solution, and a body constituting a support upon which said tubes are mounted, the convolutions of the tubing containing the non-freezing solution being nested between the convolutions of the refrigerant receiving tube and serving as a holdover.

6. In a refrigerating apparatus, an expansion coil unit comprising a refrigerant receiving tube, tubing for a non-freezing solution in thermal contact with said refrigerant receiving tube and a hollow body of low thermal conductivity forming a material receiving compartment, upon which said tubes are mounted in thermal contact therewith.

7. In a refrigerating apparatus, an expansion coil unit comprising a refrigerant receiving tube, tubing for a non-freezing solution in thermal contact with said refrigerant receiving tube and serving as a hold-over and a hollow body constituting a support upon which said tubes are mounted, said body being of low thermal conductivity for allowing the ready transmission of heat therethrough to the interior thereof.

In testimony whereof I affix my signature.

THOMAS C. WHITEHEAD.
